Primary Examiner—Joel Sincavage*Attorney, Agent, or Firm*—Salter & Michaelson[57] **CLAIM**

The ornamental design for a heater pad switch, as shown and described.

DESCRIPTION

FIG. 1 is a perspective view of a heater pad switch showing our new design;

FIG. 2 is a right side view thereof;

FIG. 3 is a left side view thereof;

FIG. 4 is a top plan view thereof;

FIG. 5 is a front elevational view thereof;

FIG. 6 is a rear elevational view thereof; and,

FIG. 7 is a bottom plan view thereof.

The characteristic feature of the instant design is the appearance of the front panel of the switch.
